FIG. 5

FIG. 6

closure E remote from the cemented side, by turning of the link 8 by means of a lever 18, and it thereby folds down the closure E and also exerts a variable counter pressure on the bar 1 (FIGURE 2).

A number of nozzle bores 19 open at the cement-receiving surface 1a of the bar 1 and are connected through a common duct 20 in the bar and a flexible pipe 21 incorporating a control valve 22, to a source of compressed air (not shown). Carbon dioxide, nitrogen or any other gas having the required properties, can be used instead of air, or for example use may be made of air charged with hardening accelerators, or heated air. When the control valve 22 is opened, the gas concerned flows through the nozzle bores 19 against the cement K present between the bar 1 and the roll folded closure E, whereby a quantity of this cement is forced over the area covered by the bar 1 and between the walls of the package bounding the cut edges S of the roll folded closure E. This ensures a proper sealing of the closure.

Finally, it should be mentioned that the present invention is not limited to the use of blowing nozzles with the particular form of applicator member illustrated in the drawings. Blowing nozzles may, within the scope of the invention, be associated with other forms of cement applicator members, for example cementing segments or cementing rollers, in instances where the cement to be applied is required to reach places which are difficult of access.

I claim:

1. A method of cementing the closure joint of a package, said method comprising applying a mechanical cement applicator member to the sealing surface of the joint to transfer cement thereto, and directing a pressurized gas from the applicator member onto the cement applied to the closure joint to force the cement into said joint.

2. A method as claimed in claim 1, wherein the pressurized gas is heated.

3. A method as claimed in claim 1, wherein the pressurized gas is air.

5 4. An apparatus for cementing the closure joint of packages, said apparatus comprising a mechanical cement applicator member, means coupled to said mechanical cement applicator member for applying same to the sealing surface of a closure joint to be cemented to transfer cement thereto, and at least one blowing nozzle associated with the mechanical cement applicator member and arranged to direct a pressurized gas onto the cement applied to the closure joint to force the cement into said closure joint.

15 5. An apparatus as claimed in claim 4, in which the mechanical cement applicator member is a cementing bar incorporating blowing nozzles which extend transversely with respect to the bar and open adjacent the leading edge of the cement-receiving surface of the bar.

20 6. An apparatus as claimed in claim 5, in which the cement-receiving surface of the cementing bar is of concave form.
